United States Patent Office

Des. 196,813
Patented Nov. 5, 1963

196,813

BOTTLE

Bruce L. Roberts, Rossford, Ohio, assignor to Owens-
Illinois Glass Company, Toledo, Ohio, a corporation of Ohio

Filed May 9, 1962, Ser. No. 70,053

Term of patent 14 years

(Cl. D58—6)

FIG. 1

The back and side not shown are the same as the front and side shown.

I claim:

The ornamental design for a bottle, substantially as shown and described.
